DESCRIPTION

FIG. 1 is a top plan view of a rolling wrist support for use with a computer mouse showing our new design;
FIG. 2 is a front view thereof;
FIG. 3 is a rear view thereof;
FIG. 4 is a side view thereof;
FIG. 5 is a side view thereof showing the side opposite that shown in FIG. 4;
FIG. 6 is bottom plan view thereof; and,
FIG. 7 is a perspective view thereof, on a reduced scale, the broken line drawing of a forearm, hand and mouse is for illustrative purposes only and forms no part of the claimed design.
